UNITED STATES PATENT OFFICE

98,689

DESIGN FOR A PORTABLE ELECTRIC FOOD MIXING DEVICE

Raymond E. Patten, Bridgeport, Conn., assignor
to General Electric Company, a corporation of
New York

Application August 8, 1935, Serial No. 58,009

Term of patent 14 years

To all whom it may concern:

Be it known that I, Raymond E. Patten, a citizen of the United States, residing at Bridgeport, in the county of Fairfield and State of Connecticut, have invented a new, original, and ornamental Design for a Portable Electric Food Mixing Device, of which the following is a specification, reference being had to the accompanying drawing, forming part thereof.

The accompanying drawing shows in Fig. 1 a perspective view, and in Fig. 2 a top plan view

of a portable electric food mixing device embodying my new design, a portion being removed in Fig. 2 so as to illustrate more clearly certain portions of the design.

I claim:

The ornamental design for a portable electric food mixing device substantially as shown, and described.

In witness whereof, I have hereunto set my hand.

RAYMOND E. PATTEN,
